Specification for Design. Patented Aug. 22, 1922.

Application filed January 11, 1922. Serial No. 165. Term of patent 14 years.

To all whom it may concern:

Be it known that I, GEORGE M. LUDLOW, a citizen of the United States, residing at Evanston, in the county of Cook and State of Illinois, have invented a new, original, and ornamental Design for Computing Scales, of which the following is a specification.

In the accompanying drawing, forming part of this specification—

Figure 1 is a front elevation of a computing scale embodying my new design; and Figure 2 is a side elevation of the same.

I claim:

The ornamental design for a computing scale as shown.

GEORGE M. LUDLOW.
